UNITED STATES PATENT OFFICE.

THEODORE A. WILLARD, OF CLEVELAND, OHIO, ASSIGNOR TO WILLARD STORAGE BATTERY COMPANY, OF CLEVELAND, OHIO, A CORPORATION OF WEST VIRGINIA.

CONNECTOR AND CONNECTION FOR STORAGE BATTERIES.

1,225,298.

Specification of Letters Patent.

Patented May 8, 1917.

Application filed July 16, 1915. Serial No. 40,189.

To all whom it may concern:

Be it known that I, THEODORE A. WILLARD, a citizen of the United States, residing at Cleveland, in the county of Cuyahoga and State of Ohio, have invented a certain new and useful Improvement in Connectors and Connections for Storage Batteries, of which the following is a full, clear, and exact description.

10 This invention relates to a terminal connector and connection for storage batteries, and has for its chief object to provide a construction which overcomes many of the difficulties attending the use of tapered plug 15 connectors heretofore employed on storage batteries.

More specifically considered, the invention aims to provide a connection of which the connector of the battery is a part, which 20 is strong and compact and has low resistance and wherein the coöperating parts are very tightly connected and will not be corroded by the acid from the battery.

Additional advantages reside in the large 25 area of contact and in the accessibility of tightening or loosening the parts and the ease with which the parts can be assembled and disassembled.

The above and their objects are attained 30 by my invention which may be briefly summarized as consisting in certain novel details of construction and combinations and arrangements of parts which will be described in the specification and set forth in 35 the appended claims.

In the accompanying sheet of drawings Figure 1 is a top plan view of a portion of a storage battery equipped with my invention; Fig. 2 is a sectional view through the 40 several parts of the connection including the terminal connector of the battery; Fig. 3 is a view similar to Fig. 2, showing the parts separated; and Fig. 4 is a sectional view showing a slight modification.

45 Referring now to the drawings, 10 represents a battery jar and 11 one of the battery terminal connectors, which is preferably formed of lead. The body of this terminal has a socket which receives the 50 terminal post 11^a of the battery extending up through the cover of the battery jar, the post and connector being lead-burned together. The connector 11 is provided with a lateral extension 12 of less depth than the 55 body part of the connector, this extension

being some distance below the top of the connector, as shown in Fig. 2. Buried in the connector is an insert 13 of relatively hard good conducting metal, such as brass or copper, which extends in a horizontal direction 60 through the lateral extension 12 into the body part of the connector where it is provided with a portion in the shape of an annulus which surrounds the terminal post 11^a. The other end of the insert is provided 65 with a conical boss or head 14 extending or protruding from the top of the terminal extension 12 near the outer end thereof. In the construction shown in Figs. 2 and 3 this boss or head of the insert is 70 provided with a tapped or threaded opening for a clamping screw.

Coöperating with and adapted to be electrically connected to the tapered part of the 75 insert is a terminal 15 for a flexible conductor 16. This terminal, which is formed of good conducting material, such as brass or copper, has a flattened portion provided near its end with a socket 17 tapered in opposite directions from the center. The 80 lower tapered part of the socket fits onto the tapered head 14 of the insert and the upper tapered part of the socket receives a correspondingly tapered screw head or nut of a binding device which is utilized to 85 draw the terminal members together. In the construction shown in detail in Figs. 2 and 3, I utilize a cap screw 18 having a threaded shank which enters into the threaded socket of the head 14 of the insert 90 and an integral head which is tapered on the exterior and fits into the upper tapered part of the socket 17. When the screw is tightened the terminal 15 is pulled tightly into contact with the tapered head of the 95 insert, and at the same time the tapered head of the screw is drawn tightly into the tapered socket of the terminal 15. The screw may be formed of copper, brass or other good conducting material. 100

In the modification shown in Fig. 4, the protruding head of the insert here designated 19 is provided with an integral threaded stud 20 which receives a nut 21 tapered on the exterior and adapted to draw together 105 the tapered parts of the insert and terminal 15 and to tightly engage in the socket of the terminal. The construction is otherwise the same as that first described.

In both constructions the exposed metal 110

parts, including the tapered head of the insert, the head of the screw, the nut and the terminal of the conductor, are coated or otherwise covered with lead so that they 5 will not be corroded by the acid of the battery. This can be done by plating or by casting the lead onto the parts. The lead coating is shown in Figs. 2, 3 and 4, and in said figures is designated by the reference 10 character 22.

With many of the prior tapered plug connections utilized with storage batteries the parts could not be drawn together tightly enough to prevent the creepage of 15 acid between the engaging parts, and in consequence the parts would corrode and could not be easily disassembled or taken apart, and when assembled did not fit together closely enough to provide a joint of the required 20 low resistance. On the other hand, with my invention the previously enumerated and other advantages are attained to a very high degree. The joint or connection has low resistance due to the large area of 25 contact between the engaging parts and to the fact that the terminal 15 has tapered portions which are forced very tightly into contact with both the insert and binding screw or nut. In fact, the parts virtually 30 grind into each other so tightly that the acid cannot creep between the contacting surfaces. Additionally, the binding screw is accessible and the parts can be easily assembled and disassembled; the terminal 35 15 can be pointed or directed in any direction with respect to the battery terminal; and the height of the connection is minimized, this latter being due partly to the fact that the nut or screw enters into the socket of the terminal 40 15 and partly to the fact that the battery terminal extension to which the terminal 15 is directly connected is lowered or offset from the top of the battery terminal or connector.

Having thus described my invention, what I claim is:—

1. A storage battery connector or terminal, comprising a body having a socket for a battery terminal post and having an insert 50 provided with a protruding part to which a conductor may be connected.

2. A connector or terminal adapted for storage batteries, comprising a body having an insert of relatively hard material, said 55 insert having a projecting tapered portion to which a terminal of a conductor may be connected.

3. A connector or terminal for storage batteries, comprising a body having a socket 60 for a terminal post and having a lateral extension projecting from the socketed part,

an insert of relatively hard material buried in said extension and provided with an outwardly projecting part to which a terminal of a conductor may be attached. 65

4. A connector having a body portion provided with a socket for a terminal post of a battery and with an insert of relatively hard material, said insert having a portion extending around said socket and a tapered 70 projecting part to which a terminal of a conductor may be attached.

5. A storage battery connector having a body portion provided with a socket for a terminal post and having an extension, an 75 insert of relatively hard material buried in the connector and extending through the extension and around the socket of the body portion of the connector, said insert having near one end of the extension a projecting 80 part to which a terminal of a conductor may be attached.

6. In a connection adapted for storage batteries, a battery connector or terminal and a conductor terminal, one of said terminals having a tapered projection and the other having a socket tapered in opposite directions, said projection engaging one part of said socket, and clamping means for drawing the parts together having a tapered 90 part engaging in the other part of said socket.

7. In a connection for storage batteries, a battery connector or terminal having an insert with a tapered projecting portion, a 95 conductor terminal having a socket tapered in opposite directions, one part of the socket fitting into the tapered part of the insert, and a clamping device engaging said insert and having a tapered portion which fits into the other tapered part of the socket.

8. In a connection for storage batteries, a battery connector or terminal having a lateral extension displaced from the top thereof, an insert of relatively hard material in said extension and having a projecting tapered portion, a conductor terminal having a tapered portion in engagement with the tapered portion of the insert, and a threaded clamping device for drawing said tapered portions together.

9. In a connection for storage batteries, a battery connector or terminal having an insert provided with an exteriorly tapered portion, a conductor terminal having a tapered socket engaging said tapered portion of the insert, and means for clamping the parts together comprising a device having a threaded portion engaging the insert. 115

In testimony whereof, I hereunto affix my signature in the presence of two witnesses.

THEODORE A. WILLARD.
